AND ONE-THIRD TO GEORGE H. ALLAN, OF ST. LOUIS, MISSOURI.

PISTON-RING.

1,247,949.

Specification of Letters Patent. Patented Nov. 27, 1917.

Application filed May 5, 1916. Serial No. 95,622.

To all whom it may concern:

Be it known that I, JOHN W. FORD, a citizen of the United States, and resident of St. Louis, Missouri, have invented certain new and useful Improvements in Piston-Rings, of which the following is a specification containing a full, clear, and exact description, reference being had to the accompanying drawings, forming a part hereof.

My invention relates to piston rings and is especially directed to the composite type, that is, the type of rings having more than one part.

15 The primary object of my invention is to construct a ring wherein the one part is of a material such as cast iron arranged to bear against the wall of the cylinder, and the other part arranged to fit within the 20 first mentioned part of cast iron which second mentioned part is constructed of material preferably spring steel, and having a relatively increased elastic or spring quality over the first mentioned or outer 25 part whereby to produce a ring having a relatively great elastic quality and with a surface of a material not likely to injure the cylinder wall.

A further and more specific object of my 30 invention is to construct a ring of a plurality of parts comprising an outer channeled element the peripheries of the walls of which channel are concentric with the periphery of the body of the channel thereby 35 forming in effect a concentric packing ring, and which element has the inner periphery of its body portion eccentric to the outer periphery of the body portion, the said element having free ends at a point where said 40 body portion is of its least thickness, such channeled eccentric element or part arranged to contain a second part or element constructed of material having a relatively greater elastic or spring quality and whose 45 inner periphery is eccentric to its outer periphery so that when placed within the first mentioned part or element its inner periphery will be concentric with the outer periphery of the other element and in effect 50 producing a concentric ring composed of eccentric parts.

With the above purposes in view my invention consists in certain details of construction and arrangement of parts as will 55 be hereinafter fully, clearly and concisely

set forth in my specification, pointed out in my claims and illustrated by the accompanying drawings, in which

Figure 1 is an elevation of a ring partly in section embodying my improvements and 60 constructed in accordance with my invention, the ring being shown in its normal or extended condition;

Fig. 2 is an elevation of the ring contracted or reduced in diameter from its 65 normal condition as when in place between a piston and cylinder;

Fig. 3 is an enlarged transverse sectional elevation taken on the line 3—3 of Fig. 1;

Fig. 4 is an enlarged transverse sectional 70 elevation taken on the line 4—4 of Fig. 1;

Fig. 5 is a sectional elevation taken on the line 5—5 of Fig. 7;

Fig. 6 is a fragmental plan on an enlarged 75 scale showing the lap joint of the free ends of the outer element of my composite ring in an extended condition;

Fig. 7 is a view similar to Fig. 6 showing the same in a contracted condition as when in use;

Fig. 8 is a plan on an enlarged scale 80 showing fragments only of the inner and outer elements of my composite ring and the free ends of the inner element extended in their normal position and their relation 85 to a stop pin, and

Fig. 9 is a view similar to Fig. 8 showing the parts in a contracted condition as in use, the stop pin engaging the free ends of the inner element to hold it against rotation 90 relative to the outer element.

Referring by numerals to the accompanying drawings, 10 designates the outer element and 11 the inner element of my composite ring. By preference the outer ring 95 is constructed of cast iron or a material of like quality which is least likely to cut or wear the wall of a cylinder.

As shown, the element 10 has an eccentric body portion 12, that is the inner periphery of the body of the element 10 is eccentric to its outer periphery.

Leading inwardly from each side of the eccentric body portion 12, are the walls 13, which walls have their inner peripheries 105 parallel or concentric with the outer periphery of the element thereby producing a channel of unequal depth circumferentially of the element.

This element 10 has free ends each of 110

which ends including substantially one-half of the body portion for a portion of its length and one of the walls 13 for a portion of its length being cut away leaving a substantially L-shaped end 14, the circumferential boundaries of said ends being substantially along the median line of the ring. This element is preferably made from a cast iron tube as is common, of greater diameter than the cylinder in which it is to be employed, and cut after being separated from said tube to produce free ends to permit of its being sprung over the piston and into the cylinder so that it will normally tend to spring outwardly against the cylinder. The said ends 14 are arranged to overlap each other whereby to prevent axial or transverse seams through the ring to prevent the passage of gas or steam from one end of the cylinder to the other.

The inner ring 11 is also preferably constructed from a tube but of a much more elastic material preferably spring steel. This ring is placed in the channel of the outer ring with its free ends diametrically opposite the free ends of the outer ring, its body forming with the body of the outer ring a composite ring of concentric arrangement.

Extended through the body of the ring 10, diametrically opposite its free ends, is a stop pin 15, arranged to engage the free ends of the inner ring so that when in use there can be no rotational movement between the element 10 and element 11, that is, the inner and outer rings are thus held against relative rotational movement.

It will be apparent that by reason of the materials employed in the two elements of my composite ring I have a structure whose outer periphery is of such material as to create a minimum of wear upon the cylinder wall and is of itself possessed of concentric inner and outer peripheral surfaces which at all times prevent spaces between the cylinder and piston to prevent leakage of gas or steam therethrough. It will be further apparent that the ring or structure carries an element constructed of spring steel or a material having relatively great elastic qualities to bear outwardly against the softer body to hold the said softer body in intimate non-leaking contact with the cylinder wall. Such a ring by reason of the eccentric arrangement of the two bodies entering into its structure is a perfectly balanced ring having like weight at all points circumferentially thereof and is a ring in which the parts of one ring or composite structure are interchangeable with the parts of like other structures, that is, the inner element of any one of my rings will fit the outer element of any other ring of my design, or vice versa.

It is to be particularly noted that the stop pin 15 is located at a point removed from

the free ends of the outer cast iron element or ring 10, and preferably at a point where the body of the element 10 has the greatest sectional dimensions.

By this expedient the pin is placed where it in no wise interferes with the complete closing or bringing together of said free ends as is common, and in this manner avoids the necessity of shaping said free ends to close over a stop pin as is common.

By this expedient also the stop pin is placed at a point where the ring has the greatest body, and for this reason is least likely to break at the point of the stop.

While I have described the inner element 11 of my ring as being constructed of spring steel or a material possessing greater elasticity than the outer element, I do not wish to be understood as limiting myself to spring steel. The desideratum in the material of the said inner ring is a high carbon steel preferably inter-mingled with nickel, which is highly elastic, either cold or heated as when in use, so that it will have great elasticity during service, the nickel tending to prevent carbon deposits therein and other corrosion. It will be apparent that it is not practicable to employ such a material next the cylinder walls for the reason that due to its hardness it will not readily conform to uneven or worn cylinder walls but will scratch and produce excessive wear tending to deteriorate the cylinder surface. It is for this reason that I provide such nickel or high carbon steel element with a shoe or outer element having a surface of a material equal in softness or softer than the material of the cylinder walls.

Having thus described my invention what I claim as new therein and desire to secure by Letters-Patent of the United States, therefor is:

1. A piston ring comprising two elements, one of which consists of a ring-like body having its inner periphery eccentric to its outer periphery and having a wall at each side of said body, the outside faces of said walls being of uniform heights throughout the circumference of the element and the inside faces of non-uniform heights and a pin secured in the body at a point where its cross sectional dimensions are greatest, said pin projecting inwardly from the inner periphery of the element the other element being of substantial ring shape with its inner and outer periphery relatively eccentric and having free ends arranged to engage with the said pin, the said elements when united forming a ring structure of substantially uniform cross sectional dimensions throughout, with said walls of the one element flush with the outer periphery of the other element.

2. A piston ring comprising two elements, one of which consists of a ring-like body

having its inner and outer peripheries relatively eccentric, a wall at each side of said body, the inner peripheries of which walls are concentric with the outer periphery of the body of the ring, the other element consisting of a ring-like body having its peripheral faces relatively eccentric and whose thickness corresponds with the heights of said walls, so that when the two elements 10 are united there will be a substantially uni-

form cross-section throughout, each of said elements having free ends, and means to prevent relative rotation of the elements.

In testimony whereof, I have signed my name to this specification, in presence of 15 two subscribing witnesses.

JOHN W. FORD.
